Primary Examiner — Elizabeth Albert(74) Attorney, Agent, or Firm — Michael J. Feigin, Esq.; Feigin & Associates, LLC(57) CLAIM

The ornamental design for the hookah head, as shown and described.

DESCRIPTION

FIG. 1 shows a top perspective view of a hookah head.

FIG. 2 shows a bottom perspective view thereof.

FIG. 3 shows a front elevation view thereof.

FIG. 4 shows a rear elevation view thereof.

FIG. 5 shows a right side elevation view thereof.

FIG. 6 shows a left side elevation view thereof; and,

FIG. 7 shows a top plan view thereof.

The broken lines shown in the drawings illustrate portions of a hookah head for illustration purposes only, and form no part of the claimed design.
